[57] **CLAIM**

The ornamental design for a closure, as shown and described.

DESCRIPTION

FIG. 1 is a perspective view of the closure of the subject invention shown in the open position.

FIG. 2 is a top plan view of the closure of FIG. 1, the broken line showing of lettering forming no part of the claimed design.

FIG. 3 is a right side view of the closure of FIG. 1, the opposite side being identical.

FIG. 4 is a rear view of the closure of FIG. 1.

FIG. 5 is a front view of the closure of FIG. 1; and,
FIG. 6 is a perspective view of the closure of FIG. 1, shown in the closed position.

The bottom and interior of the closure form no part of the claimed design.
